(57) **CLAIM**

The ornamental design for a bottle, as shown and described.

DESCRIPTION

FIG. 1 is an elevated, perspective view of a bottle (portions not claimed shown with broken lines);

FIG. 2 is an elevated view of the front thereof (portions not claimed shown with broken lines);

FIG. 3 is an elevated view of one side thereof (portions not claimed shown with broken lines);

FIG. 4 is an elevated view of the other side thereof (portions not claimed shown with broken lines);

FIG. 5 is a plan view of the top thereof (portions not claimed shown with broken lines); and,

FIG. 6 is a plan view of the bottom thereof (portions not claimed shown with broken lines).

The broken line showing in FIGS. 1-6 is for illustrative purposes only and forms no part of the claimed design.
